FASTENING MEANS FOR BAG FRAMES AND
THE LIKEPreston Upham, Newton, Mass., assignor to
United-Carr Fastener Corporation, Cambridge,
Mass., a corporation of Massachusetts

Application April 2, 1936, Serial No. 72,325

3 Claims. (Cl. 150—29)

My invention relates to bag frame structures in combination with fastening means for the same and has for its object to provide a fastening means of simple construction carried by the bag frames in such a way that it will not interfere with the means for attaching the hand bag fabric to the frames.

In the drawing, which illustrates a preferred embodiment of my invention:

10 Fig. 1 is an elevational view of a bag frame structure and fastening means for the same;

Fig. 2 is an enlarged top plan view of the fastening means shown in Fig. 1 with the frames in open position;

15 Fig. 3 is an enlarged rear view of my improved main fastener member attached to one of the frame members;

Fig. 4 is a bottom view of the fastener installation shown in Fig. 3;

20 Fig. 5 is a fragmentary front view of the installation shown in Fig. 3;

Fig. 6 is an enlarged section taken on the line 6—6 of Fig. 1; and

25 Fig. 7 is an enlarged section taken on the line 7—7 of Fig. 1.

Referring to the drawing, I have shown in Fig. 1 a pair of frame members 1 and 2 secured together at their free ends by rivets 3 or any other suitable fastening means which will permit the 30 members to be hinged together for relative swinging movement of one to the other. The frame members 1 and 2 with which my improved separable fastener means is used are of the U-shaped cross-section type, as best illustrated in Figs. 6 and 7, having an outer wall 4, an inner wall 5, and a base portion 6 connecting the two walls. The walls 4 and 5 are spaced apart to form an outwardly opening channel (Figs. 6 and 7). The inner wall 5 has a flange 7 integral therewith 35 and extending in substantially right angular relationship to the inner wall. In my preferred form, as illustrated in Figs. 6 and 7, the outer wall 4 is bent away from the inner wall 5 so that the bag material (not shown) may be 40 brought over the outer wall 4 of each frame member and clenched in the channel between the inner and outer walls by a subsequent bending of the outer wall toward the inner wall.

The frame members 1 and 2 are held in locked 45 position by a separable fastening means, as most clearly shown in Figs. 2 and 6, comprising a main fastener member 8 secured to the frame member 1 and any suitable interengaging means carried by the frame member 2, such as the projection 9, pressed from the material of the flange 7.

Although I prefer to use my separable fastener means with frame members of the type described, it should be understood that the fastening means may be used advantageously with frame members of other cross-sections.

Before the main fastening member 8 is secured, a portion of the flange 7 of the frame member 1 is cut away, as most clearly shown in Figs. 3 and 5, so as to leave an opening in the flange substantially in the center of the frame member. 5 Next the material of the flange 7 adjacent to opposite ends of the opening is slotted as at 10 (Figs. 3 and 5) thereby forming lugs 11 for a purpose which will be hereinafter more fully described.

The main fastening member 8, as best illustrated in Figs. 3—7, comprises, in my preferred form, a knob means 12 of any suitable shape or material superposed upon a one-piece plate member. The plate member has a flange portion 13 at one end and an L-shaped attaching portion 14 at the other end having a foot portion 14 and an upwardly extending portion 15. When the plate member is finally assembled with the frame member 1 the L-shaped portion is secured in the U-shaped cross-section in such a way that the foot portion 14 is positioned at the bottom of the U-shaped cross-section (Fig. 6) in substantially adjacent relation to the base portion 6, and the upwardly-extending portion 15 lies substantially adjacent to the inner wall 5 (Figs. 6 and 7) 20 having portions at opposite ends disposed between the flange 7 and the frame base portion 6 (Fig. 5). The foot portion 14 is useful as an aid to maintaining the plate member in fixed position within the cross-section, but I do not wish to be limited to the same because satisfactory attachment to the frame member has been provided with this portion omitted. The portion 15 has a reduced neck portion 15a extending through the opening in the flange 7 and joining the flange portion 13 to the main body of the portion 15 (Fig. 5). The plate member is held in secure attachment to the frame member by means of the lugs 11 which are bent to clamp the upwardly-extending portion 15 of the plate member firmly 30 against the inner wall 5, as most clearly shown in Figs. 5 and 7. After the plate member has been secured in final position the flange portion 13 35 overlies the outer edge of the wall 5 between the lugs 11 and extends from the portion 15a toward the frame member 2. The knob 12 is attached to the portion 13 in any suitable way such as by a nail or screw means 16 (Fig. 4) headed on the lower side of the portion 13 and extending through

apertures (not shown) in the portion 13 into engagement with the material of the knob 12.

A fastener socket means 17 (Figs. 2, 4 and 6) is provided, in my preferred form, as an integral part of the flange 13 and adapted for cooperative fastening engagement with the projection 9. The socket means 17 is preferably formed by indenting the portion 13 to form a recess of bow-shaped cross-section, as best illustrated in Fig. 6. However, I do not wish to be held by the specific form of separable fastening means illustrated and described because it is apparent that there may be an interchanging of the means relative to the parts with which they are associated or slight modifications made in the form of the means without departing from the spirit of the invention.

In the normal operation of the fastening means which I have just described, when the frame members 1 and 2 are moved into closed position, the free edge 18 of the flange portion 13 will engage the projection 9 and as pressure is applied to opposite sides of the frame construction, mostly the natural resiliency of the frame members will permit the edge 18 to ride over the projection 9 until the projection snaps into locking engagement with the recess socket means 17. The frame members may be readily separated by a slight tipping of the knob 12 to disengage the cooperating fastening means.

It is apparent that by my invention I have provided a separable fastening means which is adapted to operate entirely independently of the means for securing the bag material to the frame. Furthermore, my fastening means is of relatively simple and inexpensive construction capable of easy assembly with the respective frame members with which it is adapted to be used.

Although I have illustrated and described a preferred embodiment of my invention, I do not wish to be limited thereby because the scope of my invention is best set forth in the following claims.

I claim:

45 1. A bag frame structure including a pair of frame members hinged together at their free ends, each of said frame members having an outer wall and an inner wall forming an outwardly opening channel whereby a bag material may be secured in said channel between said outer and inner walls, said inner walls each having a flange means extending outwardly from the upper edge thereof, the flange means of the inner wall of one of said frame members having an opening in one portion thereof, said inner wall having at least one attaching lug integral therewith and extending into the channel of said frame member, and a fastening member independent of the securing means for the bag material, said fas-

tening member having a plate portion clamped to said inner wall by means of said attaching lug, said plate portion extending upwardly through the opening of said flange, and a flange portion integral with said plate portion and disposed above said inner wall, the said flange portion having an integral separable fastening means, and cooperating fastening means carried by said other frame member. 5

2. A bag frame structure including a pair of frame members hinged together at their free ends, each of said frame members having an outer wall and an inner wall forming an outwardly opening channel, said inner walls each having a flange extending outwardly from the upper edge thereof, the flange of the inner wall of one of said frame members having an opening in one portion thereof, attaching lugs integral with the outer edge of said last mentioned inner wall, and a fastening means including a projection integral with the flange of one of said inner walls and a cooperating fastener member carried by the other of said inner walls, said fastener member comprising an L-shaped attaching plate having a foot portion positioned within the channel of the other of said inner walls and a side portion secured to said last mentioned inner wall by means of said attaching lugs, a flange portion integral with said side portion and adapted to overlie the flange of said first mentioned wall 30 when said frames are in closed position, said flange portion having an indentation therein adapted to receive the projection on the flange of said first mentioned inner wall for securing the frame members together, the cooperating parts 35 of said fastening means being engaged and disengaged through the natural resiliency of said frame members, and a fastener operating means carried by said flange portion. 25

3. A bag frame structure including a pair of hingedly connected outwardly opening channelled frame members, each having spaced inner and outer walls presenting a channel for the reception of bag material, an outwardly extending flange integral with the inner wall of at least one frame member, said flange being recessed from its outer edge to substantially the plane of the inner face of the inner wall, a fastener plate positioned within the channel of the flanged frame member and formed with a reduced neck 45 extending through said recess above said flange, means integral with said flange engaging the inner face of said plate for holding said plate against the inner wall of the said frame member, an angular extension on the upper end of said reduced neck extending toward the other frame 50 member and cooperative fastener means between said extension and the other frame member. 55
